UNITED STATES PATENT OFFICE.

GUSTAVE BASTHEIM, OF PITTSBURGH, PENNSYLVANIA.

DESIGN FOR A PIN, BROOCH, BRACELET, FINGER RING, OR ARTICLE OF SIMILAR NATURE.

Application filed February 16, 1922. Serial No. 734. Term of patent 3½ years.

To all whom it may concern:

Be it known that I, GUSTAVE BASTHEIM, a citizen of the United States, residing at Pittsburgh, in the county of Allegheny and State of Pennsylvania, have invented a new, original, and ornamental Design for a Pin, Brooch, Bracelet, Finger Ring, or Article of Similar Nature, of which the following is a specification, reference being had to the accompanying drawings, forming part thereof, in which—

Figure 1 is a perspective view of a ring having my new design applied thereto;

Figure 2 is a development illustrating my new design; and

Figure 3 is a side elevation of the development shown in Figure 2.

I claim:

The ornamental design for a pin, brooch, bracelet, finger ring, or article of similar nature as shown.

In testimony whereof, I have hereunto set my hand.

GUSTAVE BASTHEIM.
